ADJUSTABLE GUIDE AND TRACK FOR SLIDING DOOR

Victor J. Bukolt and Albert A. Jurgella,
Stevens Point, Wis.

Application February 4, 1954, Serial No. 408,096

4 Claims. (Cl. 16—87)

This invention relates to horizontally slidable doors or panels for cabinets and analogous manufactures made of wood.

Some cabinets and other articles of furniture or the like made of wood are now more extensively provided with sliding panels than with hinged doors in order to give ready access to the interiors of such containers or receptacles; but after a short period of use it frequently happens that these sliding panels or doors bind and do not slide easily. Such poor performance may be due to various causes such as warping, swelling or shrinkage of the lumber, sagging of the frame or other distortion of the cabinet, etc. While various means have been proposed for adjusting such sliding doors to overcome this drawback, they have been rather complicated and expensive.

The object of this invention is to provide an extremely simple and inexpensive means for adjustably supporting and guiding horizontally slidable panels or doors in wood cabinets and the like, the structure being such that the panels may not only be initially installed at a low cost, but may be quickly and easily adjusted to slide freely if the cabinet should become distorted.

With the above and other objects and advantages in view, the invention resides in the novel combinations and arrangements of parts and the novel features of construction hereinafter described and claimed, and illustrated in the accompanying drawings which show the present preferred embodiments of the invention.

In the drawings:

Fig. 1 is a front view of a portion of a cabinet or the like embodying the invention, parts being broken away;

Fig. 2 is a vertical sectional view taken on line 2—2 in Fig. 1;

Fig. 3 is an enlarged detail of a portion of Fig. 2; and

Fig. 4 is a perspective view of one of the adjusting screws.

Referring more in detail to the drawings the numeral 10 denotes generally a cabinet or the like having an opening in its front or side closed by one or more horizontally slidable panels 11. In furniture cabinets such as the one illustrated, there are usually two panels or door members disposed in forwardly and rearwardly spaced relation so that when they are in their closed positions they will slightly overlap and close the entire open front of the cabinet, each panel being slidable in further overlapped relation to the other to expose portions of the interior of the cabinet. Each of the two panels shown is made of wood and is of rectangular shape, and each may be provided with a suitable handle or handhold conventionally represented at 12. The cabinet illustrated includes a top 13, a bottom 14, a rectangular body having four corner posts or legs 15 connected by upright walls 16 on three sides, the fourth or front side being open and closed by the sliding panels. The front opening of the cabinet may extend horizontally from one front corner post or leg to the other and vertically from an upper guide member or rail 17 to a lower guide member or

rail 18 which latter may form a part of the bottom of the body as seen in Fig. 2. The panels or door members are thus disposed within a rectangular frame which includes the upper and lower guide members and upright side members.

The guiding means for the top of the panel or panels may be variously constructed but as shown there are two parallel and laterally spaced channels 19 which extend longitudinally of the upper member or rail 17 and face downwardly to receive the top portions of the panels. The latter slide freely in these guide channels which are deep enough to permit some upward adjustment of the panels as later described. As shown, the channels are formed by a depending stop strip or flange 20 at the rear of the member 17, a parting strip 21 between the two panels and a front stop strip which may be a piece of molding, the strips 21 and 22 being removably secured to the bottom of the member 17.

The improved means for supporting and adjusting each of the panels comprises a longitudinal groove or channel 23 routed or otherwise formed in the top of the lower track member or rail 18 immediately beneath the panel, the groove receiving the lower ends of at least two longitudinally spaced pin-like supporting elements which are preferably wood screws 24 screwed into the bottom of the panel. The track channels 23 may be of inverted T-shape in cross-section and into the arms or branches of their cross portions 25 are slid metal strips 26 which form wear resisting bottoms for the channels to slidably support the lower ends of the screws. Since the longitudinal edges of the strips extend into the wider lower portions of the channels they will be prevented from lifting or rolling out of the channels. Either or both of the supporting elements or screws 24 may be formed with enlarged heads 27 with rounded extremities 28 to contact with the metal strips and reduce friction, since the two screws or pin-like supports on each panel support the entire weight of it. The height of the heads 27 is about that of the vertical side wall portions 29 of the inverted T-shaped channels and their width or thickness is a little less than the spacing of the portions 29 so that the heads move freely between the portions 29. Instead of forming screw driver kerfs in the screws, their heads are preferably of octagon shape in cross-section, or they have flat side faces to be engaged by a wrench or similar tool to facilitate screwing their pointed ends 30 into the bottom of the panels. It will be apparent that by properly adjusting either or both of the screws on a panel or door member it may be caused to tilt in a vertical plane to adjust it to the square of the cabinet should the latter become distorted. Thus a vertical edge of the door or panel may be brought into parallelism with the adjacent upright side member of the frame. This adjustment also facilitates the initial installation of the panels or doors and reduces the cost of manufacture. Further it allows for considerable variations in the sizes of the parts; and the invention is especially useful in the production of the less expensive grades of cabinets and furniture.

While the panels may be inserted and removed by removing the strips or moldings 21—22, the latter may remain permanently attached to the top member 17 if the channels 19 are made sufficiently deep to enable the tops of the panels to be pushed upwardly into them a sufficient distance to permit the screws to be moved into and out of the channels 23. In order to prevent the space between the bottoms of the panels and the top of the lower member 18 from being seen at the front of the cabinet, a molding strip 31 may be removably secured by brads or screws along the top of the front portion of the member 18 in slightly spaced relation to the front of the outermost panel. A similar molding strip 32 may

be removably fastened to each of the front legs 15 so that when the panels or doors are in their closed positions the outer vertical edges of the panels will not be visible. It will be understood that the panels may be of any length and that any number of the supporting and adjusting screws may be used on each panel.

From the foregoing, taken in connection with the accompanying drawing, it will be seen that novel and advantageous provision has been made for carrying out the objects of the invention, and while preferences have been disclosed, attention is invited to the possibility of making variations within the scope of the invention as claimed.

We claim:

1. An adjustable guide and track means for a horizontally sliding door of a cupboard or like article of furniture comprising a horizontally disposed track member having in its top a longitudinally extending track-forming channel with a bottom and opposed sides, and at least two rigid elements adapted to extend downwardly from the bottom of a door at longitudinally spaced points, the lower projecting portions of said elements extending into said track channel and being slidable therein with their lower extremities resting on the bottom of the track channel to sustain the weight of a door, the opposite sides of the channel preventing lateral movement of the lower end of the door, at least one of said elements

5 being a wood screw adapted for threading in the bottom of a door and adjustable to permit tilting of the door in its vertical plane.

2. The structure of claim 1 in which said screw has an enlarged guiding head adapted for sliding engagement with the opposite sides of the channel.

3. The structure of claim 1 in which said screw has an enlarged guiding head adapted for sliding engagement with the opposite sides of the channel, said head being 10 provided with a rounded bottom and with means for engagement by a turning tool.

4. The structure of claim 1 in which each of said elements is a wood screw with its threaded end adapted for vertical adjustment in the lower edge of a door to 15 permit tilting of the latter in its vertical plane.
